UNITED STATES PATENT OFFICE

140,055

DESIGN FOR A REEL FOR ELECTRIC CONDUCTOR CORDS

John McLeod Little, Toledo, Ohio, assignor to Manning, Maxwell & Moore, Inc., Muskegon, Mich., a corporation of New Jersey

Application March 22, 1944, Serial No. 113,004

Term of patent 7 years

(Cl. D41—1)

To all whom it may concern:

Be it known that I, John McLeod Little, a citizen of the United States, residing at Toledo, in the county of Lucas and State of Ohio, have invented a new, original, and ornamental Design for a Reel for Electric Conductor Cords, of which the following is a specification, reference being had to the accompanying drawing, forming part thereof.

Figure 1 is a perspective view of a reel for electric conductor cords, embodying my new de-

sign, the lead off guide for the conductor cord being shown in broken lines.

Fig. 2 is a similar view showing the reel for electric conductor cords, from the side opposite that shown in Fig. 1.

The drawing is lined for contrasting colors.

I claim:

The ornamental design for a reel for electric conductor cords, substantially as shown and described.

JOHN MCLEOD LITTLE.
